Modern Plastics, May, 1965, p. 95, Tableware Line by Federal Housewares, Condiment Shakers shown.

[73] Assignee: Gemco-Ware Inc.

Primary Examiner—Winifred E. Herrmann
Attorney, Agent, or Firm—Armand E. Lackenbach

[] Term: 14 Years

[57] CLAIM

[21] Appl. No.: 604,940

The ornamental design for a pepper mill or the like, substantially as shown and described.

[22] Filed: Aug. 15, 1975

DESCRIPTION

[51] Int. Cl. .... D7—06

FIG. 1 is a perspective view of a pepper mill or the like, showing my new design;

[52] U.S. Cl. D7/53; D9/164;

FIG. 2 is a top plan view thereof; and

D9/287

FIG. 3 is a side elevational view thereof.

[58] Field of Search D7/47, 153, 155, 53,
D7/52, 54; D9/162, 164, 284, 287

The characteristic feature of my design resides in the cap portion having fluted upper walls with a lower adjacent indented smooth band.
